UNITED STATES PATENT OFFICE.

GEORGE LYTTON CLOSE, OF MOUNT VERNON, NEW YORK, ASSIGNOR, BY MESNE ASSIGNMENTS, TO SHIP SCARF COMPANY, A CORPORATION OF NEW YORK.

NECKWEAR.

No. 923,409.

Specification of Letters Patent. Patented June 1, 1909.

Application filed September 25, 1908. Serial No. 454,772.

To all whom it may concern:

Be it known that I, George LYTTON CLOSE, a citizen of the United States, and a resident of Mount Vernon, Westchester county, State of New York, have invented certain new and useful Improvements in Neckwear, of which the following is a specification.

My invention relates to neckwear, and is particularly adapted to neckwear worn with what is commonly known as two-fold collars in which the band of the neck tie lies between the two folds of the collar when placed in position. In ordinary neckwear, as is well known to all who have worn those two fold collars, it is very difficult to adjust the tie after it is placed around between the folds of the collar and frequently in attempting to adjust it the strain placed upon the neck band of the tie is so great that it stretches it out of shape and sometimes tears it. In my invention I seek to overcome this by making the neck band of the tie thinner, particularly that part of the neck band adjacent to the collar of the wearer.

In Figures 1 and 2 I have shown my invention as applied to the ordinary neck tie having the continuous ordinary interlining. In Figs. 3 and 4 I have shown my invention applied to a neck tie in which interlinings of the ordinary thickness are placed in the tying ends of the tie, while in the neck band or a portion of same a much thinner interlining is placed. In Figs. 5 and 6 I have shown my invention in a neck tie in which separate interlinings are placed in the tying ends. Figs. 7 and 8 represent plan views of a neck tie embodying my invention.

In the drawings, A is the outer face of the tie and B the inner face, which may or may not be made of the same material as the outer face.

In Figs. 1 and 2, C is the ordinary continuous strip of interlining placed in neck-wear.

In Fig. 1, D D are two thin strips of rubber or other waterproof material adapted to cause the interlining and the outer face and inner face A and B to adhere to the interlining, which are placed therein while the tie is being assembled. After the tie is assembled as shown in Fig. 1, it is the ordinary practice in the manufacture of neckwear to pass a heated iron over same. As this is done the rubber is dissolved forming

a cementlike substance which as it cools will cause the inner and outer faces A and B respectively to adhere to the interlining C.

In Figs. 3 and 4, E E are the interlinings placed in the tying ends of the tie of ordinary thickness which are sewed to a very thin piece of material F to form the interlining of the neck band.

In Figs. 5 and 6, E E are independent interlinings placed in the tying ends of a tie of ordinary thickness and stitched to the tie at a suitable point to hold them in place, and in this form of my invention it will be noted that I dispose of any interlining in the neck band or in a portion of the neck band of the tie so that after the inner and outer faces A and B have been caused to adhere together by the waterproof cement there will be but two thicknesses of material in the neck band or a portion of the neck band which by reason of their being cemented together will practically be a solid strip of material. The use of the waterproof cement D is of great utility in that it will permit of my invention being applied to washable ties; it will overcome any possibility of the cemented parts of the neck band coming apart by reason of any perspiration reaching the neck band when in use and has many advantages of this nature which are readily seen, for instance, among others, if a material was used that was not waterproof the tie would be liable to become stained if washed or if water reached it.

In Fig. 7 I show a plan view of a neck tie containing my invention as shown in Figs. 1 and 2.

In Fig. 8 I show a plan view showing my invention as shown in Figs. 5, 6 and 7, the row of stitching G connecting the independent interlinings with the outer fabric of the neck tie proper.

Other modifications may be made without departing from my invention.

What I claim as new and desire to secure by Letters Patent, is:

1. In a necktie the combination of tying ends and a neckband, the plies of a portion of said neckband being cemented together by a waterproof cement so as to form substantially a single strip of material.

2. In a neck tie the combination of two tying ends connected together by a neck band, an interlining in said neck band, a portion of the neck band being cemented to

the interlining by a waterproof cement so as to form substantially a single strip of material.

3. In a neck tie, the combination of two tying ends connected together by a neck band, independent interlinings in the tying ends, and a portion of the plies of the fabric of the neck band being cemented by waterproof cement, so as to form a substantially solid neck band.

4. In a neck tie the combination of tying ends and a neck band, interlinings in the tying ends, an interlining in the neck band substantially thinner than the interlinings in the tying ends, the said interlining in the neck band being cemented to the outer ma-

terials of the neck tie by a waterproof cement so as to form substantially a single strip of material.

5. In a necktie an interlining for a neck tie consisting of a strip of material, a portion of which is covered by a waterproof cement adapted to be fixedly secured in the neck tie by an application of heat.

In testimony whereof, I have signed my name to this specification, in the presence of two subscribing witnesses.

GEORGE LYTTON CLOSE.
